JOHN MACDONALD PURCELL, OF VENICE, CALIFORNIA, ASSIGNOR TO GEM CARBURETER AND AUTO SPECIALTY COMPANY, OF OAKLAND, CALIFORNIA, A CORPORATION OF ARIZONA.

CARBURETER.

1,171,401.

Specification of Letters Patent.

Patented Feb. 8, 1916.

Application filed March 5, 1913. Serial No. 752,209.

To all whom it may concern:

Be it known that I, JOHN MACDONALD PURCELL, a citizen of the United States, residing at Venice, in the county of Los Angeles and State of California, have invented new and useful Improvements in Carbureters, of which the following is a specification.

This invention relates to carbureters for volatile liquid fuels, wherein an explosive mixture is provided for internal combustion engines, more particularly to that class and description for manufacturing a combustible gaseous mixture from hydro-carbons having an extremely high point of ebullition.

The primary object of the invention is to provide a carbureter of the above general relation which is especially adaptable for use in automobiles of the various different kinds, but more particularly adaptable for providing a very economical mixture of volatilized liquid fuel for the internal combustion engines supplied in most of the smaller automobiles now in use, so that the said automobiles may be driven in the streets of cities or in traffic congested localities at a rate of speed much less than is now possible.

Another object of the invention is the provision of an improved carbureter of the character stated, which may be used in any of the larger or more heavy types of self propelled vehicles, among which the modern commercial trucks are to be included, in which the carbureted mixture is manufactured from that form of hydrocarbon more commonly designated as distillate.

Another object of the invention is the provision of improvements of the above stated character in which the carbureted mixture is furnished in the form of a very fine, uniform mixture of previously heated air at atmospheric pressure and carbureted liquids, very highly vaporized; the arrangement being such that when it is desired to drive a vehicle containing a motor of the "Ford" or "Buick" types very slowly a uniformly proportionate mixture is provided, thereby saving considerable energy on the part of said motor by a substantial reduction in its speed, and as the speed of the vehicle is increased, the proportions of the constituents of said vaporized mixture are changed.

A further object of the invention is to provide valve and port construction so arranged as to produce a series of whirling or vortex currents of the air utilized by said carbureter, and thereby produce a more thoroughly and uniformly mixed vaporized combustible fuel.

A still further object of the invention is the provision of a carbureter that is superior in point of relative simplicity and inexpensiveness of construction, positiveness in operation, and efficiency, and serviceability.

With the above and other objects in view the invention further consists in the new and novel provision, formation, construction, combination, organization and relative arrangement of parts, members and features, all as hereinafter more particularly described, shown in the drawings and finally pointed out in the claims.

In the drawings: Figure 1 is a vertical cross-sectional view of the invention, certain parts being broken away; Fig. 2 is a fragmentary sectional view taken on the line X^2-X^2 of Fig. 1, looking in the direction of the appended arrows; Fig. 3 is a fragmentary sectional view, taken on line X^3-X^3 of Fig. 1, looking in the direction of the appended arrows; Fig. 4 is a detail view of various parts shown in Fig. 7; Fig. 5 is a fragmentary detail view showing a section of the usual exhaust pipe in connection with which the air heating pipe is used; Fig. 6 is a fragmentary view showing another portion of the air heating pipe and its connection with the hot air jacket; Fig. 7 is a vertical exterior view of the parts shown in Fig. 1; Figs. 8 and 9 are fragmentary detail views of parts shown in the several other views; Fig. 10 is a sectional view taken on line $X^{10}-X^{10}$ of Fig. 1, showing the valve and post construction; certain parts being removed to more clearly illustrate the arrangement of the ports; Fig. 11 is a fragmentary sectional view taken on line $X^{11}-X^{11}$ of Fig. 10; Fig. 12 is a sectional detail view taken on line $X^{12}-X^{12}$ of Fig. 1, looking in the direction of the appended arrows; and Fig. 13 is a modification of the port construction shown in Fig. 11.

Like characters of reference denote like parts and combinations of parts throughout the several views of the drawings.

Referring with particularity to the drawings, the invention comprises the receptacle A for containing the distillate or other forms of hydrocarbons and B denotes the regulating means from the source of fuel supply (not shown) to said receptacle A.

C denotes the central portion of the carbureter which has its lower end formed as a tube a fitted within the receptacle A and having a venturi c extending upwardly therein, which venturi opens into the general circulating chamber D, where a whirling, or vortex, motion of the air admitted to said chamber is created by the ports E and F, the specific formation of which will be hereinafter more fully described.

G denotes the annular valve which operates on the ports E to regulate the quantity of air to be admitted to said chamber D; said valve being readily adjusted by the turning of the valve adjustment means H.

I denotes the air jacket around the valve G and the ports E and F which is supplied with previously heated air conducted through the conduit d to said jacket as hereinafter more fully described.

J represents the upper portion of the carbureter in the form of a bolting flange, to which the invention is fastened, and which in turn is fastened to a portion of the bed-plate K of the motor.

L denotes the throttling means extending through the chamber D' in the flange part J communicating with the valve operating means L' in the chamber D.

M denotes the tension means disposed between the annular valve G and the valve adjustment means H, the same being provided in the annular housing M'.

The receptacle A specifically comprises the annular chamber 13 the confines of which are the walls 14 and 15 and the base wall 16. Extending from one side of the said receptacle A and communicating therewith is the auxiliary distributing chamber 17 showing a threaded flange 19 at its upper portion into which is preferably fitted an ordinary pipe plug 20 having the opening 20^a therein for the intake of air. The regulating means B comprises the float 21 which may be made of suitable material and of suitable thickness such as a hollow metallic float or pontoon, and is suspended into said chamber 13 as by the lever 22 fulcrumed as at 23 by the pin 23^a.

On the other end of the lever 22 is the relatively enlarged portion 24 into which is fitted the ball end 25 of the valve 26; said ball having a seat 27 in said part 25 and there being a stem 27^a extending downwardly through a suitable opening 27^b. The valve 26 has extending downwardly therefrom the guide-rod 28 which is projected into the chamber 29 directly below the valve-seat 30. The chamber 29 and the valve-seat 30 both being in

lug 31 which has connected thereto the pipe or conduit b which distributes the carbureting liquid from a tank or other source of fuel supply (not shown) to the valve 26. The pin 23^a may be fastened in the walls of said auxiliary chamber 17, and the float 21 may be cut away as at 21^a to allow proper clearance of the wall 15 as the quantity of carbureting liquid in the chamber 13 is varied, as will be hereinafter more fully described.

Located centrally of the receptacle A is the circular way 32 provided by the walls 15 into which extends the lower end a of the carbureter. The main or central portion of the carbureter C comprises said lower end a 80 preferably threaded into the way 32 as at 32^a there being a cover 33 fitting around the portion C, covering the chamber 13 and fitting in the walls 14 as at 33^a. Immediately above said cover 33, the portion C is slightly 85 enlarged so that the fitting shoulders 34 are thereby provided, such enlarged portion having the lugs 35 of equal length extending therefrom diagonally opposed to each other. The annular base 36 immediately above said 90 lugs 35 provides a rest for the shell 37; such shell comprising the annular housing M' and having an inwardly extending wall as at 38 at its upper part, there being a relatively reduced upstanding portion or flange 95 39 which latter is threaded as at 39^a. The wall 40 extends upwardly from said base 36 to a point coincident with said upstanding flange 39 and is threaded at its upper end as at 40^a; said threaded portions 39^a and 100 40^a having the bolting-flange J threaded thereon when the various parts comprising the invention have been assembled as hereinafter fully set forth. Ports E are provided in said wall 40 angularly inclined toward each other in three groups approximately as shown in Fig. 10 but angularly opposed to each other with respect to the different groups, so that a whirling or vortex motion is imparted to the air drawn into 110 the conical circulating chamber D (an approximation of said motion of the air being shown by the arrows in Fig. 10) through the ports F in the base 36 from the air jacket I which is provided by the shell 41, resting 115 on the cover 33 and has its upper end flanged inwardly as at 42, there being threads 43, provided at the inner edge of said flange 42 and threads 43^a on the outer upper part of the shell 37, so that the latter may be turned 120 into said jacket I.

In the chamber M' is a spring M coiled intermediate the annular valve G, which has an upstanding flange 44 thereon of predetermined height and in proportion to the areas of said ports E and F, and the ring 45; said ring 45 having a series of pins 46, fitting in suitable opening 47 in the wall 38 of said shell 37; said valve G having a ring 48 of suitable non-leakable material fas- 125 130

tened on its under side for contact with the base 36, so that when said valve G is closed the air in said jacket I is not drawn into said chamber D. The chamber D is so designed 5 as to conform approximately to the lines shown in Fig. 1, wherein the lower portion is of conical and concave formation and has the spider-brace 49 extending thereacross as shown in Fig. 12, for the double purpose of 10 guiding the valve-stem 50 and for breaking up or spraying the liquid to be carbureted as the latter flows from the nozzle 51, when the needle valve 52 is moved away from the seat 53 in the upper end of said nozzle as 15 hereinafter fully described; said nozzle extending upwardly in the inverted conical chamber or venturi c in the end a to a point coincident with the reduced portion as at 20 54, where the upwardly inrushing air is concentrated or strangled when the carbureter is used for furnishing an ideal volatilized 25 combustible mixture for unusually low speed of the motor supplied, either with or without taking any air from the jacket I through the ports E and F. The nozzle communicates 30 with a conduit 51^a, which extends into the chamber 13 as at 51^b.

The bolting-flange J may be fastened in any desired location in, on or about a vehicle, but it is preferable to fasten the same to 35 that part of the motor which is provided with an opening corresponding with the chamber D', which latter also corresponds with the chamber D. In the chamber D' the throttling damper or butterfly valve 55 is provided on the rod 56, which projects through the walls 57 of said flange portion J. On one 40 end of the said rod 56 is the lever 58 of said throttling means L and on the opposite end the lever 59 is fastened, there being a block 45 60 journaled in the outer end of said lever 59 through which the rod 61 extends. The rod 61 is rotatably fastened to the outer end of a like lever 62, the inner end of said 50 lever 62 being fastened to the rod 63 extending into the chamber D as well as the lugs 35. A spring 64 is fastened in said chamber D as shown in Fig. 2 and has its 55 end in tensional contact with the cam or roller 65 provided on said rod, so that any movement of the levers 58, 59 or 62, which 60 may be attached to a rod (not shown), extending from the usual foot treading throttle, will open or close or partially open or close the damper 55 and proportionately open or close or partially open or close the valve 52, which latter may have its stem 50 fastened to the spring 64. The lugs 35 are of equal length so that interchangeability of 65 the throttling means L and L' may be had and the same used on either side of the carbureter as may be desired.

The air jacket I is designed to be supplied with air and drawn through the conduit d along and over a portion of the motor

exhaust pipe 66 and the heat of said exhaust pipe will thereby heat the air to a fairly high degree, previous to its being drawn into said jacket by the vacuum created by the normal propulsive completing cycle 70 of the motor in operation.

The valve adjustment means H comprises a cap 67 threaded on the inside, so that it may be turned on the threads 43^a of the shell 37; said threaded portion 43^a having 75 therein the vertical grooves 68 as shown in Fig. 8, into which the end 69 of the spring 70 projects through the wall of said cap, as the same is rotated in either way to adjust the compression of the spring M on the annular valve G, the spring being fastened to the cap as at 71. The rod 61 is threaded at its upper end so that the thumb-nuts 72 may be used to lengthen or shorten the distance 80 between the block 60 and the lever 63. 85

The ports F are shown to have the V shaped parts 73 projecting thereinto, for it is found in the practice that they are the means of assisting in directing the air currents in approximately the whirling or vortex motion shown. Said ports E and F may be provided with air controlling surfaces in the form of indentures 74 as in the modification shown in Fig. 13, for it is found in the practice that the various projections as at 90 73 or the indentures as at 74, provided on or in the walls of said ports are the means of directing or deflecting said currents of air to create said whirling or vortex motion. The ports E in the annular wall 40 of the 100 portion C have their upper edges of inclined downward angularity as at 75, and have their lower edges 76 also extending downwardly as they extend inwardly, the latter edges being of concave formation; both of 105 said edges in practice producing the desired deflection of said air currents as the same are drawn through said ports and impinged on said edges.

With regard to Fig. 10 of the drawings 110 the shell wall 41 of the jacket I and the flange 44 of the valve G have been omitted in order to more clearly show the approximate formation and the arrangement of the ports E and F.

I do not desire to be understood as limiting myself to the specific formation, provision, construction, combination, organization, and relative arrangements of the parts, members and features, as herein shown and described, but reserve the right to vary the same in the further utilization of the invention, and in and within the terms of the following claims.

Having thus fully described my invention, 125 what I claim and desire to secure by Letters Patent, is:

1. A carbureter for producing a volatilized combustible mixture, comprising a portion 130 having a circulating chamber therein; a

- 41
- venturi communicating with said chamber; a carbureting liquid container communicating with said venturi; means for regulating the quantity of liquid contained in said container; valve means in said venturi for discharging a quantity of liquid therein; means for moving said valve; air controlling means in said chamber; throttling means for controlling said last named means; means for 5 heating a quantity of air; an air jacket for containing said heated air; a series of ports communicating with said chamber; another series of ports communicating with said air jacket; and valve means under tension for 10 controlling the quantity of heated air taken into said chamber substantially as described.
- 15 2. A carbureter for producing a volatilized combustible mixture, comprising a portion having a circulating chamber therein for producing whirling or vortex currents 20 of volatilized mixture; a venturi communicating with said chamber and having a relatively reduced strangulation portion therein; a carbureting liquid container communicating with said venturi; means for regulating the quantity of liquid contained in 25 said container; valve means in said venturi for discharging a quantity of liquid therein; means for moving said valve and controlling the quantity of said liquid discharged; air controlling means in said chamber for 30 controlling the proportion of air taken therein; throttling means for controlling said last named means simultaneously with 35 said valve moving means; means for heating a quantity of air; an air jacket for containing said heated air; a series of ports communicating with said chamber; another series of ports communicating with said air jacket; and valve means under tension for 40 controlling the quantity of heated air taken into said chamber, substantially as described.
- 45 3. A carbureter for producing a volatilized combustible mixture, comprising a portion having a circulating chamber therein; a venturi communicating with said chamber; a carbureting liquid container communicating with said venturi; means for regulating the quantity of liquid contained in 50 said container; valve means in said venturi for discharging a quantity of liquid therein; means for moving said valve; air controlling means in said chamber; throttling means for controlling said last named means; means for heating a quantity of air; an air jacket for containing said heated air; a series of ports communicating with said air jacket; an annular valve under tension for controlling said 55 quantity of heated air taken into said chamber; and adjustment means for varying the tension of said valve to produce most minute adjustment of the air taken into both series of ports; said deflecting surfaces of said ports producing a whirling or vortex motion of the carbureted mixture in said chamber, substantially as described.
- 60 65 4. A carbureter for producing a volatilized combustible mixture, comprising a portion having a circulating chamber therein; a venturi communicating with said chamber; a carbureting liquid container communicating with said venturi; means for regulating the quantity of liquid contained in said container; valve means in said venturi for discharging a quantity of liquid therein; means for moving and controlling the movement of said valve; air controlling means in said chamber; throttling means for controlling 70 75 80 85 90 95 100 105 110 115 120 125 130

said last named means; means for heating a quantity of air; an air jacket for containing said heated air; a series of ports angularly inclined from each other, communicating with said chamber and having deflecting edges therein; a second series of ports angularly inclined in their relation to each other, having deflecting surfaces therein and communicating with said air jacket; an annular valve under tension for controlling said quantity of heated air taken into said chamber; and adjustment means for varying the tension of said valve to pro-

duce most minute adjustment of the air taken into both series of ports; said deflecting surfaces of said ports producing a whirling or vortex motion of the carbureted mixture in said chamber, substantially as described. 15

In testimony whereof, I have signed my name to this specification in the presence of the two subscribing witnesses.

JOHN MACDONALD PURCELL.
